To all whom it may concern:

Be it known that we, EARLE V. HENNECKE and DAVID KUSKIN, citizens of the United States and residing at Flushing and Astoria respectively, in the county of Queens and State of New York, have invented a new, original, and ornamental Design for a Windshield Wiper Motor, of which the following is a specification, reference being had to the accompanying drawing, forming part hereof and in which:

Fig. 1 is a top plan view of a windshield wiper motor showing our new design,

Fig. 2 is a front elevational view thereof,

Fig. 3 is a rear elevational view thereof, and

Fig. 4 is a bottom view thereof.

We claim:

The ornamental design for a windshield wiper motor substantially as shown.

EARLE V. HENNECKE.

DAVID KUSKIN.
